United States Patent Office.

LUMAN F. JOHNSON, OF BUFFALO, NEW YORK.

Letters Patent No. 82,721, dated October 6, 1868.

IMPROVEMENT IN FURNACE-DOORS.

The Schedule referred to in these Letters Patent and making part of the same.

TO ALL WHOM IT MAY CONCERN:

Be it known that I, LUMAN F. JOHNSON, of the city of Buffalo, county of Erie, and State of New York, have invented a certain new and useful Improvement in Furnace-Doors; and I do hereby declare that the following is a full and exact description thereof, reference being had to the accompanying drawings, making a part of this specification, in which—

Figure I is an elevation,

Figure II a vertical section, and

Figure III a horizontal section.

My invention relates to a door for furnaces, composed of a cast-iron frame lined with fire-brick, and consists in protecting the flange or flanges of the cast-iron frame which hold the brick against the destructive action of the intense heat to which doors of this class are subjected, by forming the brick with a rebate, so that they may overlap said flanges, and prevent the direct action of the heat thereon, and the consequent burning thereof, as will hereinafter more fully appear.

It is a well-known fact that furnace-doors as commonly constructed, (that is, with a cast-iron frame lined with common fire-brick cemented therein,) are quickly destroyed by the heat, which burns and warps the cast-iron frame, so that it fails to retain the brick. Frequent delays in the running of the furnace are the consequent result.

In the drawings—

A represents the iron frame of the door, provided with dove-tail flanges a' a' , at the centre and at each edge. B B show the fire-bricks, which are moulded with corresponding dove-tails b' b' rebated from the edge of the brick, so that when the brick are inserted in the frame, they may overlap and cover the flanges a' a' , as clearly shown at d, so as to protect said flanges against the heat of the furnace.

This arrangement prevents the heat from the furnace from striking the cast-iron frame until it shall have first passed through the thickness of the fire-brick, when its intensity will have diminished to an extent to render its effect upon the cast iron harmless.

The external flange a' extends entirely around the door, but the part across the upper side of the door is made separate, and secured by bolts C, so that it may be taken off for the insertion or removal of the fire-brick.

It has been demonstrated by experience, that a furnace-door made according to my invention will last and keep in good order many times longer than the ordinary door in which the cast-iron frame is unprotected.

What I claim, and desire to secure by Letters Patent, is—

The rebated fire-bricks B, so arranged within the cast-iron frame, as to overlap the flanges a' thereof, and protect the same, substantially as described.
